UNITED STATES PATENT OFFICE

170,942

MEDALLION

Horace Randall, Pawtucket, R. I., assignor to The
H. M. H. Co., a corporation of South Dakota

Application June 18, 1953, Serial No. 25,548

Term of patent 7 years

(Cl. D29—2)

To all whom it may concern:

Be it known that I, Horace Randall, a citizen of the United States of America, residing at Pawtucket, county of Providence, State of Rhode Island, have invented a new, original, and ornamental Design for a Medallion, of which the following is a specification, reference being had to the accompanying drawing forming a part thereof.

I claim:

The ornamental design for a medallion, substantially as shown.

HORACE RANDALL.
